United States Patent Office

Des. 232,623
Patented Sept. 3, 1974

232,623

CARTON BLANK

Edwin C. McLaren, Minneapolis, and William M. Tolaas,
St. Paul, Minn., assignors to Hoerner Waldorf Corporation,
St. Paul, Minn.

Filed Feb. 10, 1972, Ser. No. 225,370

Term of patent 14 years

Int. Cl. D9—99

U.S. Cl. D9—245

The figure is a plan view of a carton blank showing our new design.

The dash lines represent fold lines and the carton blank is of conventional thickness.

We claim:

The ornamental design for a carton blank, as shown and described.
